UNITED STATES PATENT OFFICE.

PATRICK H. MACK, OF BRADFORD, PENNSYLVANIA, ASSIGNOR TO OIL WELL SUPPLY COMPANY, OF PITTSBURGH, PENNSYLVANIA, A CORPORATION OF PENNSYLVANIA.

PLUG PACKER.

Application filed May 11, 1921. Serial No. 468,786.

To all whom it may concern:

Be it known that I, PATRICK H. MACK, a citizen of the United States, residing at Bradford, in the county of McKean and State of Pennsylvania, have invented certain new and useful Improvements in Plug Packers, of which the following is a specification.

My invention relates to well packers, and more particularly to what are known commercially as bottom hole plug-packers, adapted for use as plugs for shutting off water, etc., from the lower level or levels of the well.

Among the objects of the present invention are, to provide a new and improved sectional plug packer formed of wood, lead, or other suitable material, and of simple, cheap and efficient construction; a packer capable of being readily placed in position at the bottom of the well, and when so positioned, easily manipulated to expand the packer structure to form a tight seal; a packer of the character stated including a body portion comprising a plurality of assembled members designed to be moved laterally or radially by a wedging action, for the purpose of expanding the packer structure during the operation of setting the packer, said movements of the members being preferably accomplished while retained against relative longitudinal movement.

A still further object is to provide a construction providing for the free passage of fluids through the packer while it is being lowered to the desired position in the well.

In the accompanying drawings, which illustrate an application of my invention,

Fig. 1 is a part elevational and a part vertical sectional view of a plug packer embodying my invention, showing the packer in the well and before it is set;

Fig. 2 is a view similar to Fig. 1, showing the packer set;

Fig. 3, a horizontal sectional view, the section being taken on line III—III of Fig. 2;

Fig. 4, a part plan and a part sectional view, the section being taken on line IV—IV of Fig. 1;

Fig. 5, a detail perspective view showing some of the members entering into the body portion of the packer;

Fig. 6, a perspective view of the packer structure, particularly showing a modifica-

tion of the means for lowering the packer into position.

Referring to the drawings, and as preferred, my improved packer structure includes a body-portion comprising a plurality of longitudinally extending members 2, a plurality of longitudinally extending wedge members 3, and an expanding plug or member 4. Members 2 and 3 are assembled to form a hollow cylindrical body of a diameter slightly less than the diameter of the hole or well it is desired to pack, said members being maintained in the desired positions for letting the packer down into the well by bottom plate 5, having a central aperture 6, and by means of a wire 7 wound around the upper ends of said members or the upper end of the packer body. The upper end of the expanding plug 4, as shown in the form of Fig. 1, is provided with a metallic cap 8, said cap being formed with a central opening 9 and a horizontal opening 10, the latter being adapted to receive a pin 11 and the opening 9 to have entered therein, so as to be secured to the pin 11, a wire 12. Wire 12 is secured to a drilling or other tool, not shown, and the packer structure is let down into the well in the usual manner of placing packer structures in wells. The body portion of the packer is secured to the lower end of the expanding plug 4 by means of nails or pins 13, the latter being passed through the members 2 of the body and having their inner ends terminating in the lower portion 14 of the plug 4.

Plug 4, as illustrated, is formed with a slight taper and its lower end, in addition to the portion 14, with a portion 15, the latter having a considerably greater taper than the remaining portion of the plug. 16 designates grooves or channels cut into the portions 14 and 15 of the plug 4, and are designed to permit the passage of fluids therethrough during the act of lowering the packer structure into the well. It will be understood that these passages 16 communicate with the central bore 17 of the body-portion of the packer.

As an additional means for permitting the free passage of fluids from the bore 17, the members 2 at their upper ends may be formed with channels or grooves 18.

In the packer structure illustrated, I have shown three members 2 and three wedging

members 3. The number of these members, however, may be varied so long as a wedging member is interposed between adjacent edges of the members 2. Members 2 are each provided with an outer curved face *a* and inner slightly inclined faces *b*; while wedge members 3 are each formed with bevelled or slightly inclined faces *c* and with a curved slightly tapering inner face *d*.

10 Members 2 and 3 are assembled to form a hollow cylindrical body having a slightly tapering central bore to receive the plug 4. In setting the packer, it will be understood that the body will be expanded by driving 15 the plug 4 into the bore of the body and that the initial movement of the plug downwardly will abruptly spread the members at the upper portion of the body, break the wire 7, and break or bend the nails or pins 13, and 20 that, in the construction shown, the expansion of the body will be effected by moving the members laterally while maintained against relative and against longitudinal movement, with respect to the walls of the 25 hole.

By effecting the expansion while the body members are maintained against longitudinal movement, I prevent the surfaces in contact with the walls from being cut or formed 30 with channels or passages, as would be the case if these surfaces were moved longitudinally while in contact with the walls of the well.

Forming a passage through the body of 35 the packer so as to permit of the passage of fluids, while lowering the packer into position, is of considerable importance in packers of this class.

While the packer structure may be made 40 of any suitable material, I find wood to be a highly satisfactory material, and when made of wood, I prefer that the expanding plug be constructed of harder wood than the sectional members constituting the body.

45 In the form of Fig. 6, I have shown different means for attaching the packer structure to the tool, not shown, in the operation of letting the packer down into the well, from the means shown in Fig. 1. In this latter 50 form, I employ eyelets 19, secured to the respective members 3, and wires 20 attached at their lower ends to said eyelets, the upper ends of the wires being secured to the tool, not shown.

55 What I claim is:

1. A plug packer comprising a circular body having series of vertically extending outer packing strips and a series of wedging strips alternately disposed between the 60 packing strips, and means operable in the body for forcing the wedging strips radially outwardly.

2. A plug packer comprising a circular body comprised of a radially disposed series 65 of vertical outer members of inwardly de-

creasing width, a second series of inner members which are alternately disposed between the outer ones and of outwardly decreasing width, and means in the body for forcing the inner members radially outward. 70

3. A plug packer comprising a circular body comprising of a series of vertically extending outer packing members, a series of wedging strips alternately disposed with the packing strips and fixed against vertical 75 movement with respect thereto either before or after the setting of the packer, and operable in the body for forcing the wedging strips radially outward.

4. A plug packer comprising a substantially round body having a series of outer packing members forming the greater portion of the outside area of the body, a series of inner wedging members alternately disposed between the outer ones, and means for 80 forcing the inner wedging members radially outward. 85

5. A plug packer comprising a substantially cylindrical body comprised of a series of vertically extending outer members, a series of inner wedging members, the outer and inner members being alternately arranged and substantially fixed against relative vertical movement, and expanding 90 means movable vertically through the body relatively to both series of members for forcing the wedging members outwardly. 95

6. A plug packer comprising a substantially cylindrical body comprised of a series of vertically extending outer members, a series of inner wedging members substantially co-extensive with the outer members, the outer and inner members being alternately arranged and substantially fixed against relative vertical movement, and expanding means movable vertically through the body relatively to both series of members for 100 forcing the wedging members outwardly. 105

7. A plug packer comprising a substantially cylindrical body comprised of a series of vertically extending outer members, a series of inner wedging members, the outer and inner members being alternately arranged and substantially fixed against relative vertical movement, and expanding means movable vertically through the body relatively to both series of members for forcing the wedging members outwardly, said body having a substantially open passage 110 therethrough which is closed by the movement of said expanding means to expanding position. 115

8. A plug packer comprising a plurality of movable members assembled to form a hollow body having a central bore, said members having longitudinally extending contacting faces a plug for effecting a lateral movement of the members for increasing the diameter of the body, said plug 120 125

having a channel in communication with the bore.

9. A plug for wells comprising a body including a plurality of longitudinally extending members and a plurality of wedge members, one wedge member being interposed between adjacent faces of two of the longitudinally extending members, said wedge members having a curved and tapering inner face, and a tapering expanding plug coacting with said wedge members for effecting a lateral movement only of the body members to increase the diameter of the body.

10 15 10. A plug for wells comprising a plurality of longitudinally extending members

and a plurality of wedge members assembled to form a hollow body, one wedge member being interposed between adjacent faces of two of the longitudinally extending members, and an expanding plug movable relatively to both the longitudinally extending members and the wedge members coacting with the wedge members for effecting a lateral movement only of the body members 20 to increase the diameter of the body.

In testimony whereof I affix my signature in presence of two witnesses.

PATRICK H. MACK.
